[57] **CLAIM**

The ornamental design for a safety razor handle, as shown and described.

DESCRIPTION

FIG. 1 is a perspective view of a safety razor handle showing my new design;

FIG. 2 is a front elevational view thereof;

FIG. 3 is a bottom plan view thereof;

FIG. 4 is a back elevational view thereof;

FIG. 5 is a top plan view thereof; and

FIG. 6 is an end view of my new design, each end being symmetrical.
